COMBINED SHADE SUPPORT AND STOP

George William Lang, New York, N. Y.

Application September 17, 1938, Serial No. 230,348

1 Claim. (Cl. 156—24)

This invention relates to shade supports and is directed more particularly to an improved construction whereby the shade spring is precluded from unrestricted unwinding in the event that the shade is inadvertently released during the manual raising or lowering of the same.

As is well known, the conventional shade roller is provided therein with a spring secured to a squared trunnion through an associated pawl and ratchet which causes the spring to be energized when the shade is drawn downwardly, whereby the spring will effect an automatic winding of the shade when the pawl and ratchet are disengaged. The shade is normally operated through any appropriate form of shade pull and it is not uncommon for this shade pull to be released before the pawl and ratchet have been properly engaged. As a result the spring rapidly acts to unwind with not infrequent damage to the shade. In order that the structure may be thereafter made operative, it is necessary to disengage the shade from its brackets and manually re-energize the spring.

These conditions have long been recognized and numerous attempts have been made to effect a satisfactory solution of this widespread nuisance. Such prior attempts have been directed mainly along two distinct lines. The first is typified by the association of shade brackets with a rod extending the full width of the window and from one bracket to the other and which rod carries a device for arresting the unwinding movement of the spring. These constructions have not been favorably received because they are bulky and expensive, unduly encumber the window frame and do not satisfactorily function for the purposes intended. The other type of construction which has been tried is characterized by the formation of a bifurcated or forked arm adapted to straddle one or both edges of the shade to form a positive stop when engaged by the hem which extends across the bottom of the shade and in which the stiffening stick is enclosed. These latter constructions act directly upon the edge of the shade and the hem. They fray the shade edge and, after a few operations, tear the hem or break the stitches which hold the hem in place. In operation they are destructive to the shade construction.

Other arrangements have been suggested but the structure of all of them is such that they materially damage the shade or force it out of shape when in use.

The present invention, in contradistinction, is so constituted that in the ordinary operation of

a shade the means which guards the spring from unrolling is wholly free from contact with the shade and does not come into engagement therewith except when the shade is inadvertently released. Then a smooth facial braking surface is presented to the hem portion of the shade where it is backed up by a shade stiffening stick and the hem and stick are caused to come into wedging engagement between a flat surface and the already wound portion of the shade, to give a soft cushioning effect which brings the shade and roller to a cushioned stop through a wedging engagement which does not place undue strains on any part of the construction and does not tend to wear or mar the shade in any way.

The structure of the present invention is, moreover, such that it is extremely economical to manufacture, can be installed by the uninitiated, requires no adjustment and embodies no moving parts. It cannot possibly get out of order, is not unsightly in appearance and is not even noticeable when associated with a shade installation.

The present invention, generally speaking, is characterized by the association directly with each shade bracket by an inclined braking flange arranged to lie in a plane substantially tangent to the circumference of a wound shade, but spaced therefrom a sufficient distance so as not to ordinarily contact therewith, but sufficiently close so as to leave less space between the flange and the shade than the thickness of the shade stick. This flange is relatively rigid, is mounted rigidly in place and forms with the shade roller an angle into which the hem with enclosed shade stick is adapted to be received when the shade is fully wound, so as to preclude further winding of the shade with consequent unwinding of the roller spring. In practice, the braking flange is formed integral with the fixture and is secured in place by the same nails or screws by which the fixture is mounted in the window frame.

Features of the invention, other than those adverted to, will be apparent from the hereinabove detailed description and claim when read in conjunction with the accompanying drawing.

The accompanying drawing illustrates one practical embodiment of the invention, but the construction therein shown is to be understood as illustrative only, and not as defining the limits of the invention.

Figure 1 is a perspective view looking at the inside of the window with a shade attached thereto by the construction of the present invention,

as applied to inside brackets. In this view certain parts of the window frame, as well as parts of the shade construction, are broken away in the interest of clearness.

5 Figure 2 is a section on the line 2—2 of Figure 1, showing the shade associated with the fixture, but with the window frame omitted.

Referring to the drawing, 1 designates a conventional window frame, 2 a shade roller of usual 10 form with associated internal spring and 3 the shade mounted on the roller and provided at its free end with a stick 4 housed within the hem 5. The roller has a circular trunnion at one end and a squared trunnion 6 at its other 15 end. The shade pull is indicated at 7. These parts are all conventional and form no part of the present invention except as associated with the devices presently to be described.

The present invention consists in the use of 20 brackets of novel and unique construction. These brackets are made in pairs with a right and a left to each pair. Each of said brackets embodies a flat plate 8 perforated with holes 9 and 10 for the passage of attaching nails 25 or screws whereby the brackets may be attached to the inner edges of the frame 1 to mount them rigidly in place thereon. These plates 8 are each provided with a stamped up boss 11 in which the hole for the shade trunnion 30 is formed. The hole at the right is circular to receive the circular trunnion of the shade, while the hole 12 at the left is in the nature of a bayonet slot to receive the squared trunnion 6. This is conventional construction and differs 35 therefrom only in the shape of the plate 8 which, as shown in Figures 1 and 2, is made to extend in an outward direction and is bent over to form an inclined flange 14, the lower edge of which is curved upwardly as indicated at 13.

40 The plate 8 is so proportioned as to locate the flange 14 in a plane substantially parallel to the axis of the roll 2 and substantially tangent but spaced slightly from the outer circumference of the fully wound shade as shown best in Figure 2. 45 The flange 14 is thus at right angles to and integral with the flat plate 8 which forms the body of the fixture so that, when the bracket is nailed in place, the flange 14 is in proper cooperative relation to the shade to be supported by the 50 bracket. The inclined relation of the flange presents a flat surface to the hem of the shade when the shade is fully rolled as shown in Figure 2 and said surface extends for an appreciable distance along the shade, so as to give adequate 55 frictional contact therewith and thus distribute wear throughout the surface of the hem, whereby it is not localized in a way to cause damage.

When the parts are assembled, they appear as 60 shown in Figure 2 from which it is clear that the circumference of the wound shade and the under surface of the flange 14 present a re-entrant angle adapted to receive the shade stick without any localization of wear. As the shade is more or less soft when wound up on the roll, 65 the shade stick when entering this angle receives

a pronounced cushioning, so that it is brought to a cushioned stop and does not come to a quick non-yielding stop as in some of the arrangements heretofore suggested and which cause appreciable damage to the shade construction. 5

With my arrangement the edge of the shade is free from wear. The stitches which hold the hem in place are likewise free from wear and the cushioning stop brought about through the operation of this invention is such as to save the shade structure, as well as the spring construction of the roller from undue strains. 10

It will be apparent from the foregoing detailed description that the shade bracket, when mounted in position on the window frame, has rigidly attached thereto a flat inclined flange substantially tangential to the wound shade and parallel to the axis of the shade roller to form, with the wound shade, the re-entrant angle in which the shade stick is cushionably received when the 20 shade is inadvertently released.

An important feature of the present invention resides in the marked economy of its fabrication, for it may be manufactured by simple die operation in quantity production at low costs. 25 The finished structures may be mounted on a window frame as simply as the ordinary shade brackets and without added cost or labor. The structure will last indefinitely and will not impose noticeable wear on the shade. Under ordinary conditions of operation the shade does not even touch the braking flange and only engages therewith when the shade is inadvertently released and rendered responsive to the spring of the roller. 30

35 The device of the present invention may be made of any appropriate materials whether they be metallic, plastics or otherwise, but I find it convenient in manufacture to stamp up the parts, which I have hereinbefore described, from sheet metal of any appropriate kind.

The foregoing detailed description sets forth the invention in its preferred practical form, but the invention is to be understood as fully commensurate with the appended claim. 45

Having thus fully described the invention, what I claim as new and desire to secure by Letters Patent is:

A one piece integral shade bracket comprising a flat plate provided with holes for the passage 50 of attaching nails or screws to mount said plate in upstanding face abutting relation to and on the inner edge of a window frame, an integral perforated boss stamped up from said plate to receive and support a shade trunnion, and a stop flange 55 integral with said plate and formed by bending a portion of the width of the plate into inclined right angular relation to the frame abutting portion of the plate and into substantial tangency with the contiguous end portion of a wound shade supported by the bracket to form with said shade a re-entrant braking angle, with said stop flange overlying the contiguous end of the shade and terminating short of the opposite end thereof. 60
